(57) **CLAIM**

The ornamental design for a ball hitch, as shown and described.

DESCRIPTION

FIG. 1 is a rear isometric view of the ball hitch;
FIG. 2 is a left side view of the ball hitch of FIG. 1, the right side view being mirror symmetrical;

FIG. 3 is a rear view of the ball hitch of FIG. 1;
FIG. 4 is a front view of the ball hitch of FIG. 1;
FIG. 5 is a top view of the ball hitch of FIG. 1; and,
FIG. 6 is a bottom view of the ball hitch of FIG. 1.
The broken lines depict portions of the ball hitch that form no part of the claimed design, and are for illustrative purposes only.
